(No Model.)

J. C. POPE.

DOOR HANGER.

No. 367,318.

Patented July 26, 1887.

John C. Pope Inventor

By his Attorney,

C. A. Swettler

UNITED STATES PATENT OFFICE.

JOHN C. POPE, OF YORKVILLE, ILLINOIS.

DOOR-HANGER.

SPECIFICATION forming part of Letters Patent No. 367,318, dated July 26, 1887.

Application filed March 24, 1887. Serial No. 232,314. (No model.)

To all whom it may concern:

Be it known that I, JOHN C. POPE, a citizen of the United States, residing at Yorkville, in the county of Kendall and State of Illinois, have invented a new and useful Improvement 5 in Door-Hangers, of which the following is a specification.

My invention is an improved door-hanger for sliding doors; and it consists in a certain 10 novel construction hereinafter first fully described, and then pointed out in the claim.

In the accompanying drawings, Figure 1, represents a perspective view of the invention. Fig. 2 represents a vertical section on the line 15 xx of Fig. 1. Fig. 3 represents a detail perspective view of one of the hangers and attachments.

Referring to the drawings by letter, A designates the door-frame, of general rectangular shape and provided with the sill a and the 20 upper longitudinal rail or beam, a' , having throughout nearly its entire length the slot B, the portions of the rails b on each sidethereof being of equal size and serving as tracks for 25 the rollers, as will be readily understood. The rails b are secured to the door-frame by means of the brackets c .

D D designate my improved hangers. They comprise the longitudinal metal bars d' , which 30 rest in the circumferential grooves f of the rollers F, which run on the rails b . At their ends these bars d' are each provided with the integral depending arms d , which pass downward through the slot B on opposite sides of 35 the roller F.

E E designate clips secured to the upper edge of the door and having their upper ends

hinged to the lower ends of the arms d . The upper ends of the clips are bifurcated, forming the ears e , which pass up on opposite sides 40 of the lower ends of the arms d , and a pivot-pin is passed through said ears and arms, as clearly shown in Fig. 3.

It is evident that the door, besides its lateral sliding motion, can be turned up on its upper 45 edge, the clips E turning upon the ends of the arms d of the frames.

The lower edge of the door or gate rests upon the sill of the frame and strikes against the strip g , secured to the sill, and prevents the door 50 from opening in the opposite direction.

The door is particularly applicable for use on barns or other buildings where it is often necessary to allow and promote a free circulation of air. The door can be propped open and 55 will serve as a protection against rain at the entrance of the barn, while allowing air to circulate therethrough to dry hay or for other purposes.

Having thus described my invention, I 60 claim—

The improved door-hanger herein described and shown, comprising the longitudinal metal bar d' , having the integral depending vertical arms d at its ends, and the clips E, pivoted 65 to the lower ends of the arms d , substantially as specified.

In testimony that I claim the foregoing as my own I have hereto affixed my signature in presence of two witnesses.

JOHN C. POPE.

Witnesses:

JOHN FITZGERALD,
HIRAM D. HUNTOON.
